Primary Examiner—Freda Nunn
Attorney, Agent, or Firm—Eric D. Levinson[57] **CLAIM**The ornamental design for a triangle-shaped movable shutter
for a data storage diskette cartridge, as shown and described.**DESCRIPTION**FIG. 1 is a top perspective view of a triangle-shaped
movable shutter for a data storage diskette cartridge accord-
ing to the present invention; and,

FIG. 2 is a bottom perspective view thereof.

Those portions of the diskette cartridge shown in broken
lines are included for illustrative purposes only and form no
part of the claimed design.**1 Claim, 1 Drawing Sheet****Fig. 1**
